UNITED STATES PATENT OFFICE.

GEORGE C. HOHEIN, OF CLARENDON, VIRGINIA, ASSIGNOR, BY DIRECT AND MESNE ASSIGNMENTS, TO THE PHOENIX MANUFACTURING COMPANY, INC., OF ALEXANDRIA, VIRGINIA, A CORPORATION OF VIRGINIA.

COPYHOLDER FOR TYPEWRITERS.

Application filed June 27, 1925. Serial No. 40,054.

To all whom it may concern:

Be it known that I, GEORGE C. HOHEIN, a citizen of the United States, residing at Clarendon, in the county of Arlington and State of Virginia, have invented certain new and useful Improvements in Copyholders for Typewriters, of which the following is a specification.

My invention is a copyholder for use in connection with typewriters and has for one object the provision of a simple, compact and efficient mechanism whereby copy will be supported at the rear of a typewriter in such position that it may be easily read by the typist, and another object of the invention is to provide novel and simple means for supporting a lens over the copy in order to magnify the line being transcribed and relieve the typist of eye strain. A further object of the invention is to provide novel means for adjusting the copyholder to the spacing of the copy so that as a line of the copy is transcribed the next line fed into view will be properly positioned to be easily read, and a still further object of the invention is to provide novel means for facilitating the insertion of the copy in the copyholder and to support the copy after it has been inserted. The invention also has for its object the provision of novel means for feeding the copy as the lines thereof are transcribed, and other objects of the invention will appear incidentally in the course of the following description. The invention is illustrated in the accompanying drawings and consists in certain novel features which will be particularly pointed out in the appended claims.

In the drawings:

Figure 1 is a perspective view of a typewriter and my improved copyholder in position for use;

Fig. 2 is a side elevation of the copyholder;

Fig. 3 is a detail view in side elevation of a portion of the copyholder viewed from the side opposite that shown in Fig. 2;

Fig. 4 is a rear elevation with the back plate of the housing or frame removed;

Figs. 5, 6 and 7 are vertical sections upon the lines 5—5, 6—6 and 7—7, respectively, of Fig. 4;

Fig. 8 is a view, partly in horizontal section and partly in plan, showing one means

for securing the copyholder at the rear of a typewriter frame, and

Fig. 9 is a similar view showing another means for securing the copyholder in position.

The typewriter, indicated at 1, may be of any make now on the market and in itself forms no part of by invention.

In carrying out the present invention, I employ a housing or frame comprising a front plate 2 to the side edges of which side plates 3 are rigidly secured, a back plate 4 being secured to the side plates at the rear edges thereof. As shown most clearly in Fig. 2, the front or face plate 2 comprises upper and lower vertically disposed portions and an intermediate connecting portion 5 which is disposed obliquely and extends rearwardly and upwardly from the typewriter machine, this formation of the front plate giving clearance for the paper inserted in the typewriter and also avoiding interference with the insertion or removal of the paper. The side plates 3 are so constructed or formed as to provide depending leg members 6 which fit closely but slidably within the central grooved portions 7 of standards 8 which are disposed in rear of the typewriter and adjacent the sides of the same. Through the standards 8 I form a plurality of transverse openings 9 and through any one of the said openings and a vertical slot 10 in the adjacent leg member 6 is fitted a bolt 11 having a nut 12 mounted upon its outer end and adapted to be turned home against the leg member whereby the latter will be secured in any desired position vertically of the standard. The copyholder can thus be adjusted to such height as best suits the convenience of the copyist. At the lower corner of each standard 8 is a foot member 13 which extends rearwardly and downwardly from the standard and has pivotally mounted thereon at its inner side a toe or shoe 14 provided with a series of openings 15 there-through disposed concentric with its pivot 16 and any one of which may be engaged by a set screw 17 mounted in the foot member 13. The toe or shoe 15 has secured to its free end a pad 18 of rubber, leather or other cushioning material which is adapted to rest upon the surface of the typewriter desk or table and thereby support the copyholder

without marring the desk or table. The standards and foot members are duplicated at the two sides of the copyholder and are connected by a brace rod 19 which receives the ends of the pivot screws 16 and also by a bracing frame 20 which is disposed immediately in rear of the typewriter and is provided at its ends immediately adjacent the standards with forwardly offset portions 21 adapted to bear against the rear post 22 of a typewriter frame. At one end the bracing frame 20 is provided in its offset 21 with a horizontal slot 23, the purpose of which will presently appear. In connection with each offset portion 21, I employ a clamp 24 which may conveniently be in the form of a plate adapted to overlap the inwardly projecting flange on the rear of the typewriter frame and having a rearwardly projecting lip 25 at its inner end to bear against the adjacent offset 21. A set screw 26 is mounted in the offset 21 and has threaded engagement with the clamping plate or bracket 24, as shown clearly in Fig. 8, whereby, if the screw be turned home, the copyholder will be firmly secured to the typewriter frame. The slot 23 permits the set screw 26 inserted therethrough to be adjusted toward or from the adjacent side of the typewriter frame and thereby accommodates typewriter frames of various widths. This manner of securing the copyholder to the typewriter frame may be employed in all makes of machines where the rear portion of the typewriter frame is open or has an open space through which the brackets or clamping plates 24 may be fitted and adjusted. Some typewriters, however, are entirely enclosed at their rear sides and one instance of such construction is shown at 27 in Fig. 9. In order that the copyholder may be connected with such typewriters, the ends of the bracing frame 20 are extended so as to project laterally beyond the sides of the typewriter, as shown at 28, and have openings formed therethrough to receive the shanks 29 of hooks 30 which are adapted to engage around the posts or rear columns of the typewriter frame, nuts 31 being fitted on the rear ends of said shanks to be turned home against the projecting ends 28 of the bracing frame to secure the copyholder in place. By pivotally adjusting the toes or shoes 14, they may be set relatively higher or lower so that the copyholder may be made to accommodate various makes of typewriters and be connected thereto notwithstanding variations in the vertical dimensions of the back plates of the typewriter frames.

As shown most clearly in Figs. 5 and 6, the upper edge of the front plate 2 is disposed somewhat below the upper end edges of the side plates 3, a line-displaying opening being thus produced above the front plate, the upper margin of said opening being defined by a cross bar or plate 32 which is secured to and extends between arms 33 and 34 which are mounted upon the shaft or journals of the feed roller 35 to rock concentric therewith. Spring fingers 36 are secured upon the bar 32 and project rearwardly from the upper edge thereof so that the copy will be directed rearwardly as it is fed through the copyholder. The arm 33 is formed integral with a handle member 37 projecting upwardly at the left side of the copyholder and also integral with a stop arm 38 which extends downwardly and somewhat forwardly, as clearly shown in Fig. 3. The lower end of the stop arm 38 is provided with a plurality of openings or sockets 39 adapted to be engaged by a stud 40 on the upper end of a leaf spring 41 secured upon the adjacent side plate 3. By manipulating the handle 37, the arms 33 and 34 may be rocked so as to set the bar 32 closer to or farther from the upper end of the front plate 2 and thereby vary the width of the line-displaying opening, the arms being held in the set position by the stud 40 engaging the socket 39 presented thereto in an obvious manner. The apparatus is thus easily adjusted to the width of the lines of copy.

At the upper front corners of the side plates 3 are secured brackets 42 having rests 43 secured to their upper ends, these rests being provided with forwardly projecting stop lugs 44 against which the ends of a lens 45 may abut whereby endwise movement of the lens will be prevented. At the lower end of each rest 43 is provided a hook or cup-like support 46 in which the lower corner of the lens is engaged whereby the lens will be firmly supported by and between the rests and at the upper end of each rest is a leaf spring 47 projecting forwardly over the rests and having its free end formed into a hook or shoulder 48 adapted to engage over the upper edge of the lens at the end thereof and fit against the front face of the lens so as to effectually retain it in place. The extremity of this spring 47 is formed into an upstanding lip 49 whereby it may be easily released from the lens to permit the removal thereof for cleaning and also to facilitate the assembling of the lens with the copyholder.

The feed roller 35 which has been mentioned is carried by trunnions or journals 50 which are rotatably mounted in the side plates 3 immediately adjacent the upper ends thereof and in the central vertical planes of the upper portions of the side plates. The roller is preferably faced with rubber or other friction material 51 whereby a good grip may be obtained upon the copy, and supported by the upper ends of the side plates 3 and extending between the same is a trough 52 which is arranged to

pass below the feed roller and guide the copy so that it will be held thereto and be caused to travel around the same. Openings 53 are formed in the trough 52 in front 5 and in rear of the transverse center thereof and friction rollers 54 are arranged to pass through the said openings and cooperate with the feed roller to yieldably grasp the copy so that, when the feed roller is rotated, 10 the copy will be fed through the copyholder. The rollers 54 are carried by rods 55 having their ends mounted in horizontal slots 56 provided in the side plates 3 adjacent the upper ends of the same and leaf 15 springs 57 are arranged to have their upper free ends bear against the rods 55 so as to press said rods toward the center of the machine to bear against the feed roller 35 at opposite sides of the vertical plane of its 20 axis. At the upper end of the back plate 4 is formed an inclined shelf 58 which is so disposed that its plane passes into the trough 52 between the rear edge of the same and the feed roller, and manuscript or other 25 matter to be copied will be guided into the trough so as to be gripped within the trough by and between the feed rollers and the presser rollers 54 cooperating therewith, the manuscript or other copy being supported by the shelf 58, as will be understood. 30 When the copy is fed into the trough, it will pass under and around the feed roller and will emerge between the feed roller and the bar 32 so that it will not drop over the front 35 of the copyholder and between the same and the typewriter to the annoyance of the copyist. As shown, the rollers 54 and the springs 57 are disposed equi-distant from the vertical plane of the axis of the feed roller 35. In 40 said vertical plane, a vertical slot 58 is formed in each side plate 3 to receive a screw or bolt 59 which engages the lower end of a cam slide 60 and connects the same with the front end of a rocking arm 61 secured to the end of a rock shaft 62 mounted in and extending between the side plates 3 adjacent the rear edges thereof and above the lower ends of the leaf springs 57. The 45 cam slide 60 is a substantially Y-shaped plate disposed between the end of the feed roller and the adjacent side plate 3, the notch 63 in the upper end of the slide spanning the trunnion or journal of the feed roller and the inclined side edges 64 of the 50 cam slide bearing upon lugs 65 on the ends of the rods 55. In the upper ends of the cam slide are vertical slots 66 which are engaged by retaining guide screws 67 inserted therethrough into the side plates so that the 55 cam slide will be properly guided and held to a rectilinear path. These screws also prevent the cam slide rocking laterally away from the side plates and creating unnecessary wear upon the ends of the feed roller or otherwise tending to choke or detract 60 from the efficiency of the apparatus. It will now be understood that normally the cam slide is in its raised position, shown in Fig. 6, so that the rollers 54 are held in engagement with the feed roller 35 or against 65 copy passing under and around said roller. If it be desired to remove the copy or insert fresh copy, a downward movement is imparted to the cam slides so that they will ride on and between the lugs 65 and thereby 70 spread said lugs and the rods 55 apart in opposition to the springs 57, consequently carrying the rollers 54 out of contact with the feed roller and to points where they will not protrude through the trough 52. A copy 75 may be inserted while these rollers are held in this retracted or depressed position and after the copy has been properly engaged in or through the trough the springs may be freed so as to again press the rollers into 80 operative position. The springs 57 may be secured in any desired manner but a very convenient method which I employ is to strike tongues 68 inwardly from the side plates 3 and rivet or otherwise secure the 85 ends of the springs to these tongues, it being understood that the frame plates of the housing are preferably of sheet metal. To rock the shaft 62 so that the rollers 54 will be withdrawn from the feed roller, I secure 90 to the right hand end of the said shaft a lever or arm 69 which extends upwardly and forwardly and is equipped at its upper extremity with an outwardly extending finger rest 70, this finger rest being slightly concave so that it may be comfortably engaged by the finger or hand of the operator. To facilitate the placing of the copy within the 95 copyholder and the bringing of the first line of the copy into position in rear of and across the line-displaying opening, a milled head or knob 71 is secured upon each of the 100 journals or trunnions 50 of the feed roller. 105 Upon the right hand journal or trunnion of the feed roller is secured a ratchet disk 110 72 disposed at the outer side of the adjacent side plate of the housing, and a spring-pressed dog 73 is pivotally mounted upon the adjacent side plate and adapted to engage the ratchet wheel 72 to prevent retrograde movement of the same. It will be noted, upon reference to Figs. 2 and 7, that the ratchet-engaging element of the dog is a roller or circular member so that under some conditions the ratchet may be rotated 115 backwardly. To actuate the ratchet 72 and thereby impart to the feed roller a step by step motion to feed the copy as the lines are transcribed, I provide a pawl 74 carried by a rocking arm or plate 75 mounted loosely 120 upon the trunnion or journal of the feed roller in such position that the pawl will ride on and engage the teeth of the ratchet. This rocking arm or plate 75 has pivotally 125 attached thereto the upper end of a link 76 130

which extends downwardly at the side of the housing and has its lower end pivoted to the rear end of a lever 77 fulcrumed between its ends upon the side of the housing, 5 a spring 78 being attached to said lever and the side plate so as to normally hold the rear end of the lever in its uppermost position. To limit the movement of this lever 77, a stop bracket 79 is secured upon the 10 side plate 3, which bracket is in the form of a plate having its ends turned outwardly to form stop lugs 80 projecting into the path of the lever, as will be understood upon reference to Figs. 2 and 4. To the front end 15 of the lever 77 is pivotally attached the upper end of a connecting bar 81 and to the lower end of this bar 81 is pivoted the rear end of an operating lever 82 which is fulcrumed upon the adjacent standard 8 and 20 projects forwardly at the side of the typewriter whereby its front end will be arranged adjacent the typewriter keys and may be equipped with a button or key 83 so that it may be easily operated. The connecting bar 81 is preferably of a telescopic or extensible construction, consisting of two similar members, one provided with longitudinal slots 84 through which stud bolts may be inserted to pass through the other 25 member and be engaged by sleeve nuts 85 whereby, when the nuts are turned home, the two members of the connecting bar will be firmly secured in a set relation. The device is thus easily adapted to the height of 30 the typewriter or other peculiarities of construction in the typewriter frame.

The width of the head of the pawl 74 is greater than the thickness of the ratchet 72 so that a gage or stop lever 86 may be 35 brought into play at times to hold the pawl out of engagement with the ratchet and also to regulate the extent to which the ratchet will be turned by the engagement of the pawl. This stop or gage consists of a plate 40 mounted loosely upon the journal of the feed roller between the ratchet and the side plate of the housing and it is formed with an edge 87 adapted to ride under the head of the pawl and hold the same out of engagement with the ratchet, as will be understood upon reference to Fig. 7. A handle 45 88 is provided and rises from the edge of this stop or gage 86 whereby the stop or gage plate may be rocked upon the trunnion 50 of the feed roller to cause more or less of the edge 87 to project under the pawl. A series of openings or sockets 89 is provided in the inner face of the plate 86 and any one of these sockets or openings may be engaged by a stop pin 90 carried by the inner 55 end of a leaf spring 91 secured upon the adjacent side plate, as shown. The engagement of the pin 90 in one of the sockets 89 will yieldably hold the stop in the position 60 to which it may be adjusted. To limit the rearward movement of the handle 88 and the stop plate 86, a stud or pin 92 is provided thereon which projects laterally inward therefrom and is located immediately adjacent the end of the edge 87. This pin 70 is adapted to bear upon the upper edge of the adjacent side plate 3 and thereby limit the rearward movement of the handle member 88. When in this position, the edge 87 will extend through the entire limit of 75 movement of the pawl 74 so that said pawl will be inoperative and will not impart movement to the feed roller whether or not the operating lever 82 should be actuated. This position of the stop plate 86 is given it 80 when copy is being inserted, and it will be noted that the pawl 74 will then have no influence upon the ratchet 72 so that the feed roller may be readily rotated in either direction by manual manipulation of the knobs 71 so as to bring the first line of the copy into proper position at the line-displaying opening below the edge of the bar 32. When the stop plate 86 is swung forwardly, the edge 87 will not extend through 85 the entire range of movement of the pawl and, consequently, the pawl will ride on the edge 87 through a part only of its movement, engaging the ratchet 72 during the remaining portion of its movement to actuate 90 the feed roller. The extent to which the feed roller may be turned each time the operating lever 82 is depressed will, consequently, be easily regulated so that the line by line feeding of the copy will be effectually 95 accomplished. By properly adjusting the position of the bar 32 and the feeding of the feed roller through the action of the pawl 74, the feeding of the copy will be regulated to conform to the size or width of the 100 lines of copy as well as to the distance between the lines.

From the foregoing description, taken in connection with the accompanying drawings, it will be seen that I have provided a 105 very compact, easily operated and durable copyholder which may be readily set up and attached to any typewriter and will support copy so that it may be read by the copyist 110 without eye strain and fed through the holder easily as the copying progresses. It will be understood that the copy, indicated at 100, is passed downwardly over the shelf 58 so as to enter the bight between the feed 115 roller 35 and the presser rollers 54 so as to be gripped by and between the same. It will then pass upwardly in rear of the bar 32 and be guided backwardly by the fingers 36 carried by said bar. When one line of the copy has been copied, pressure is applied to 120 the lever 82 in the same manner that the keys of the typewriter are operated, and this pressure will cause an upward movement of the connecting bar 81 so that the lever 77 will be rocked and the link 76 drawn down- 125 130

wardly causing the plate or pawl carrier 75 and the pawl 74 mounted thereon to rock downwardly and actuate the ratchet wheel 72 through one step. When the pressure 5 upon the operating lever 82 is removed, the spring 78 at once returns the parts to the initial normal position. It will be readily noted that the housing completely encloses the feed roller and the parts immediately 10 cooperating therewith in holding and inserting the copy so that these parts are effectually protected against damage from chance blows.

Having thus described the invention, I 15 claim:

1. In a copyholder, the combination of a housing, a feed roller mounted in the upper end of said housing, means for holding copy to said feed roller whereby rotation of the 20 roller will feed the copy, the copy being visible immediately above the front of the housing, means for rotating the feed roller, brackets secured to the upper front corners of the housing, rests carried by said brackets 25 and having stop lugs projecting forwardly therefrom, hooks at the lower ends of the rests, yieldable hooks at the upper ends of the rests, and a lens having its ends bearing upon the rests and abutting the stop 30 lugs thereon, the lower edge of the lens resting in the hooks at the lower ends of the rests and the upper edge of the lens being engaged by the hooks at the upper ends of the rests.

2. In a copyholder, the combination of a housing, a feed roller mounted in the upper end of the housing, means within the housing to cooperate with the feed roller whereby rotation of the roller will feed copy 40 through the housing in position to be read immediately above the upper end of the front of the housing, a bar extending across the upper end of the housing and forming with the front plate of the housing a line-45 displaying opening above the upper end of said front plate, and means for adjusting the said bar toward or from the upper end of the housing whereby to vary the vertical dimension of the line-displaying opening.

3. In a copyholder, the combination of a housing, a feed roller mounted in the upper end of the housing, means cooperating with the feed roller whereby rotation of the roller will feed copy through the housing to be 50 read immediately above the upper end of the front of the housing, rocking arms mounted freely upon the journals of the feed roller, means for holding said arms in a set position, and a bar secured to and extending 55 between said arms and forming with the front plate of the housing a line-displaying opening.

4. In a copyholder, the combination of a 55 housing, a feed roller mounted in the upper end of the housing, means within the

housing cooperating with the feed roller whereby rotation of the roller will effect feeding of the copy through the housing to be read above the upper end of the front plate of the housing, rocking arms freely 70 mounted upon the journals of the feed roller, a bar secured to and extending between said rocking arms and forming with the front plate of the housing a line-dis- 75 playing opening, a stop arm extending downwardly from one of said rocking arms and provided at its lower end with a plurality of sockets, and a pin mounted upon the side of the housing to yieldably engage one of said sockets.

5. In a copyholder, the combination of a housing, a feed roller mounted in the upper end of the housing, means within the housing cooperating with the feed roller to hold copy thereto, a ratchet wheel fixed to 85 one end of the feed roller, an arm mounted loosely upon the end of the feed roller, a pawl carried by said arm to engage the ratchet, a stop plate mounted adjacent the ratchet and the pawl and adapted to hold the 90 pawl out of engagement with the ratchet, a lever fulcrumed upon the housing between its ends below the said arm, a link connecting the arm with said lever, means for holding the lever normally in a raised position, 95 stops above and below said lever to limit the movement of the same, and an operating lever arranged to extend alongside a typewriter and operatively connected with the 100 first-mentioned lever.

6. A copyholder comprising a housing, means for connecting the housing to the rear of a typewriter frame, a feed roller mounted in the upper end of the housing, means co-operating with the feed roller to hold copy thereto, a ratchet fixed to one end of the feed roller, an arm mounted loosely upon the end of the feed roller, a pawl carried by said arm to engage said ratchet, a lever fulcrumed between its ends upon the housing below said arm and operatively connected with said arm, an operating lever fulcrumed below the housing and extending forwardly alongside the typewriter frame, and an extensible connecting bar pivoted at 110 its lower end to the rear end of the operating lever and pivotally connected at its upper end to the front end of the first-mentioned lever.

7. In a copyholder, the combination of a 115 housing, a feed roller mounted in the upper end of the housing, pressure rollers yieldably supported within the housing below the feed roller to cooperate therewith, and a cam slide mounted within the housing adjacent the end of the feed roller and adapted when moved downwardly to separate the pressure rollers and retract them from the feed roller, and means for actuating said 125 slide.

8. In a copyholder, the combination of a housing, a feed roller mounted in the upper end of the housing, pressure rollers disposed below the feed roller and at opposite sides of the vertical center thereof to hold copy to the feed roller, a Y-shaped slide having its upper end spanning the journal of the feed roller and its lower end disposed between the pressure rollers, means for guiding the said slide in a rectilinear vertical path, and means for vertically reciprocating said slide whereby downward movement of the slide will move the pressure rollers from the feed roller and upward movement of the slide will permit the pressure rollers to return to operative relation to the feed rollers.
9. In a copyholder, the combination of a housing, a feed roller mounted in the upper end of the housing, leaf springs secured within the housing, pressure rollers supported within the housing for movement transversely of the same, the upper ends of the springs acting on said rollers to hold them to the feed roller, a Y-shaped slide mounted in the housing for vertical movement, the lower end of the slide being disposed between the pressure rollers and the upper end thereof spanning the journal of the feed roller, a rock shaft mounted in the housing, an arm connecting one end of the rock shaft with the lower end of the slide, and means for rocking said shaft.
10. In a copyholder, the combination of standards, means for connecting the lower ends of said standards with the frame of a typewriter at the rear thereof, feet extending rearwardly from the lower ends of said standards, shoes carried by said feet, a housing secured to the standards and vertically adjustable thereon, means within the housing for supporting copy, and means carried by the housing for actuating said copy-supporting means to feed copy through the housing.
11. In a copyholder, the combination of standards, means for connecting said standards with the rear of a typewriter frame, feet members extending rearwardly from the lower ends of said standards, shoes pivotally attached to said feet members, means for securing the shoes in a set position, and pads on the free ends of the said shoes.
12. In a copyholder, the combination of a pair of standards, a housing carried by said standards, means within the housing for supporting copy, means carried by the housing for actuating said copy-supporting means whereby to feed the copy through the housing, a bracing frame extending between and secured to the standards to maintain them in fixed spaced relation and having forwardly projected longitudinally extending offsets at its ends to bear against the back of a typewriter frame to dispose the standards in spaced relation to the typewriter frame, and clamping members carried by said offsets whereby to secure the bracing frame to the typewriter frame.
13. In a copyholder, the combination of a pair of standards, feet extending from the lower ends of the standards, a housing carried by the standards, means carried by the housing for supporting and feeding copy, a bracing frame connecting the standards to maintain them in fixed spaced relation and having forwardly projected longitudinally extending offsets bearing against the back of a typewriter frame to support the standards in spaced relation to the typewriter frame, clamps carried by said offsets and adapted to engage the rear portion of a typewriter frame whereby to secure the bracing frame to said typewriter frame, one of said clamps being horizontally adjustable whereby to accommodate typewriter frames of different widths.

In testimony whereof I affix my signature.

GEORGE C. HOHEIN. [I. S.]
